Primary Examiner — R. Johnson(74) Attorney, Agent, or Firm — William G. Heedy; The Van Winkle Law Firm(57) CLAIM

The ornamental design for a chin rest, as shown and described.

DESCRIPTION

FIG. 1 is a perspective view of a chin rest showing my new design;

FIG. 2 is a perspective view thereof;

FIG. 3 is a rear elevational view thereof;

FIG. 4 is a front elevational view thereof;

FIG. 5 is a left side view thereof;

FIG. 6 is a right side view thereof;

FIG. 7 is a top plan view thereof;

FIG. 8 is a bottom plan thereof; and,

FIG. 9 is a perspective view of the chin rest, wherein the chin rest is shown in an open configuration.

In the drawings, the broken lines showing a violin in FIG. 1 form no part of the claimed design.

In the drawings, the subject matter shown in broken lines depicts parts of the chin rest that form no part of the claimed design.
